UNITED STATES PATENT OFFICE.

JOHN HOWARD WAY, OF PHILADELPHIA, PENNSYLVANIA.

CONCEALED OR INVISIBLE BUTT-HINGE.

1,249,700.

Specification of Letters Patent. Patented Dec. 11, 1917.

Application filed September 28, 1917. Serial No. 193,782.

To all whom it may concern:

Be it known that I, JOHN HOWARD WAY, of Philadelphia, in the county of Philadelphia and State of Pennsylvania, have invented certain new and useful Improvements in Concealed or Invisible Butt-Hinges, whereof the following is a specification, reference being had to the accompanying drawings.

10 My invention relates to butt-hinges of the concealed or invisible type, such as are commonly used for swinging the doors of coaches or automobiles. Such hinges comprise a fixed member, the butt of which 15 is recessed so as to form a housing to receive the pintle and the projecting portion of the movable member. The pintle being carried in the housing is thus effectually concealed. My invention has to do with 20 means for securing ready adjustment of the pintle of such a hinge within the housing, whereby the door which is thus swung may be made to more quickly and accurately fit between its jambs or pillar posts. To this 25 end I provide a readily accessible and easily actuated screw adjustment between the recessed butt or member of the hinge and its pintle.

In the accompanying drawings, Figure I, 30 is a sectional view of butts embodying my invention.

Fig. II, is a sectional view of the face of the recessed member, and

Fig. III, a cross sectional view showing 35 both members.

Fig. IV, is a view similar to Fig. I, of butts embodying a variation of my invention, and

Figs. V, and VI, are views similar to Figs. 40 II, and III, of said variation.

Referring to Fig. I, the recessed butt of my hinge comprises a pillar post plate 1, secured by screws to the pillar post. This plate is provided with a recess 2, which 45 forms the housing within which the pintle is concealed. The pillar post plate has further formed within it seats 3, 3, which receive the adjustable carrier plate 4, which carries the pintle, and comprises wings 5, 5, 50 offsets 6, 6, a back plate 7, and a pintle 8, mounted between the offsets.

The movable butt comprises the face plate 10, let into the edge of the door, the curved hinge arm 11, and the knuckle 12, through 55 which passes the pintle 8.

A difficulty constantly experienced with

butt hinges of this type has been the impossibility of securing an adjustment or readjustment when the door binds in its seat. It is the object of my invention to provide 60 a readily accessible and quickly actuated adjustment to overcome this difficulty. To this end the adjustable carrier plate 4, is attached to its seat by means of adjustment screws 20, 20. The head of each screw 65 is held in fixed relation to the carrier plate by means of the enlarged head 21, and the collar 22, forming shoulders which rotate against the two surfaces of the carrier plate. The threaded portion of each screw is received within a threaded aperture 23, in the pillar post plate. By turning these screws the adjustable carrier plate may be thrust in or out of its seat in the pillar post plate, carrying with it the pintle, and thus the required adjustment is secured. The head of 70 each of these adjustment screws 20, is let into the visible surface of the adjustable carrier plate, but otherwise is directly accessible and can be turned by an ordinary screw driver 75 whenever the door which swings upon the hinge is open.

In the variation of my invention shown in Fig. IV, the parts are the same, except for the means for securing the adjustment. 80 In this case a single screw 25, with enlarged head 26, and collar 27, rotates within the back of the adjustable carrier plate, its threaded end being received within the threaded aperture 28, in the back of the 85 housing. Accurate guidance of the adjustable carrier plate is secured by the fixed pins 29, passing through holes 30, in the wings of the adjustable carrier plate. The adjustment secured in this variation of my invention is substantially the same as in the one 90 previously described.

Having thus described my invention, I claim:

1. In a concealed hinge, the combination 100 of an adjustable carrier plate carrying the pintle of the hinge; a housing within which the adjustable carrier plate with the pintle is received and concealed; and means for adjusting the depth to which said adjustable carrier plate, and consequently the pintle, is received within the housing.
2. In a concealed hinge, the combination 105 of an adjustable carrier plate carrying the pintle of the hinge; a housing within which the adjustable carrier plate with the pintle is received and concealed; and one or more 110

screws constituting the permanent connection between the adjustable carrier plate and the housing, and by turning which the relation between the pintle and the housing is determined.

In testimony whereof, I have hereunto signed my name at Philadelphia, Pennsyl-

vania, this twenty-fourth day of September, 1917.

JOHN HOWARD WAY.

Witnesses:

JAMES H. BELL,
E. L. FULLERTON.
